I. M. PEASE

TRUSS

Filed Feb. 2, 1925

Inventor
Isaac M. Pease

By
Arthur D. Gould,
Attorney

UNITED STATES PATENT OFFICE.

ISAAC M. PEASE, OF CINCINNATI, OHIO, ASSIGNOR TO THE OHIO TRUSS COMPANY, A CORPORATION OF OHIO.

TRUSS.

Application filed February 2, 1925. Serial No. 6,335.

To all whom it may concern:

Be it known that I, ISAAC M. PEASE, a citizen of the United States, and resident of Cincinnati, in the county of Hamilton and State of Ohio, have invented certain new and useful Improvements in Trusses, of which the following is a full, clear, and exact description, reference being had to the accompanying drawings, forming a part of this specification.

My invention relates to trusses and has particular reference to trusses of the so-called hood type.

The principal object of the present invention is to provide means for strengthening the construction of a hood truss.

It has been found by experience that the points where the hood or support for the front or remedial pads of a hood truss are so weakened ordinarily by the attachment of said support to the lateral springs, that the truss soon loosens and breaks at these points. It is to overcome this difficulty that my invention is directed.

In the drawings:

Figure 1 is an elevation of a portion of the front part of a truss, illustrating the present invention.

Figure 2 is an edge view of same.

Figure 3 is a longitudinal section of the invention.

The numeral 1 indicates one of the lateral springs of a hood truss, said spring being adapted to fit to the body of the wearer in the usual manner and to carry the hood or front pad supports 2. The ends of the support 2 and spring 1 are so constructed as to overlap and are secured together by means of a sleeve or clip 3, the ends of the support 40 and spring extending beyond the opposite ends of said sleeve. Set screws 4 and 5 are threaded into the ends of the spring 1 and

hood 2, respectively, so as to engage the ends of the sleeve 3. When the parts are assembled, as shown in the drawings, and the screws 4 and 5 inserted and tightened, it will be observed that the parts are held in rigid relation to each other.

By reason of the construction above described, it will be seen that no perforations or screw holes are required in the parts of the spring or hood which are subjected to bending strains, the only perforations being at the extreme ends where no such strains are involved. The construction described, therefore, retains the entire strength of both spring and hood, thus obviating the necessity of weakening the same for the purposes of assembling the parts.

It will thus be seen that in the construction described I have provided an extremely rigid and durable means for assembling the springs and hood of a truss of the character referred to.

Having thus fully described my invention, what I claim as new and desire to secure by Letters Patent is:

1. In a truss, in combination with a spring and a supporting member, the ends of said spring and member being adapted to overlap, a sleeve arranged to encircle said ends, and studs adapted to be inserted in the ends of the spring and member beyond opposite ends of the sleeve for securing the parts together.

2. In a truss, in combination with a spring and a supporting member, the ends of said spring and member being adapted to overlap, a sleeve arranged to encircle said ends, and screws adapted to be inserted in the ends of the spring and member beyond opposite ends of the sleeve for securing the parts together.

ISAAC M. PEASE.
